ADVERTISING DEVICE

Carl G. Spandau, Fairview, N. J.

Application December 12, 1936, Serial No. 115,453

3 Claims. (Cl. 40—132)

The invention relates to advertising devices in which two sets of objects, printed matter, pictures or other things seem to appear alternately in the same place.

5 The principal object of the invention is to provide a device of this nature which is of extreme simplicity, compact, economical to manufacture and efficient in operation.

10 Other objects and advantages will become apparent as this specification proceeds. Referring to the drawings forming a part thereof:

Fig. 1 is a longitudinal sectional view taken on line 1 of Fig. 2.

Fig. 2 is a top plan view; and

15 Figs. 3 and 4 are front elevations illustrating the two different effects produced as viewed by a spectator.

20 Referring again to said drawings the device comprises a cabinet having side walls 5, a rear wall 6, a bottom wall 7 and a top wall 8. A sheet of transparent darkened material 9 is angularly disposed between the side walls 5 and divides the cabinet into two compartments 10 and 11. The lower front portion of the cabinet is open so that spectators may readily view the interior thereof.

25 The forward lower edge of the sheet 9 rests against a flange or moulding surrounding the open front of the cabinet and the rear upper edge of the sheet is supported on an angularly disposed ledge 12 which forms part of a partition extending across the upper region of the cabinet. As heretofore stated the sheet 9 is made of a transparent darkened material. This might be dark colored glass or any other darkened transparent material. The fact of the transparent material being darkened adds greatly to the efficiency of the device both in acting as a reflector and as a transparent medium.

30 Located above the sheet 9 and spaced from the top wall 8 and substantially parallel thereto is a transparent supporting member 13 forming another compartment 14. In the rear part of the compartment 14 above the transparent supporting member 13 and the darkened transparent member 9 is an illuminating means 15. The illuminating means, as illustrated, comprises a pair of incandescent bulbs. The objects to be reflected on the plate 9 are suitably located on the supporting member 13 as shown in Figs. 1 and 2. With the compartment 11 in darkness and the illuminating means 15 in operation the objects will be reflected on the darkened transparent sheet 9 as shown in Fig. 3, the sheet 9 at this time functioning as a mirror.

35 The top wall 8 or a substantial part thereof is

preferably made in the form of a slide or removable member and has a picture 16 on its underside. Obviously advertising matter or any other printed matter might be substituted for the picture. When the illuminating means 15 is functioning the picture 16 will be reflected on the member 9 behind the bottle and glass as illustrated in Fig. 3.

40 An additional effect may be provided by vertically disposing a sheet of translucent material 17 in the forward part of the compartment 14 and horizontally disposing a strip 18 of similar material which may carry suitable lettering. When this is reflected as shown in Fig. 3 it gives the effect of a platform. Obviously the compartment 14 lends itself to the accommodation of any desired objects arranged as one may see fit in order to produce varying effects.

45 The forward wall of the compartment 14 which is in line with the open end of the cabinet is provided with a member 19 which is adapted to carry suitable advertising. This advertising will appear when the illuminating means 15 is functioning.

50 Angularly disposed mirrors 20 and 21 are positioned in the rear part of the compartment 14 to intensify the light given from the illuminating means 15. These mirrors may be omitted if desired. Openings 22 may be provided in the top wall 8 for ventilating purposes.

55 The bottom wall 7 acts as a platform on which objects are placed to be viewed through the darkened transparent sheet 9 at the proper time. The objects illustrated in this instance are a tray and a bottle.

60 Illuminating means 23 are provided for the compartment 11. As illustrated this means may comprise a pair of incandescent bulbs. The back 6 of the cabinet is provided with a slide or removable member 24 which carries a picture or other suitable printed matter 25. When the compartment 10 is in darkness and the illuminating means 23 is functioning the bottle and tray and the picture 25 may be viewed directly through the darkened transparent member 9 as illustrated 65 in Fig. 4.

65 An extension 26 is located at the upper rear portion of the cabinet. The front wall 27 of this extension is formed of a member adapted to carry suitable advertising matter and this advertising 70 matter will appear when the illuminating means 23 is functioning.

75 Means are provided for alternately operating the illuminating means 15 and 23. This means comprises a flicker mechanism which is well

known in the art and it is not thought necessary to illustrate in detail. The casing 28 encloses such a mechanism.

In order that the device operate more efficiently it has been found desirable to make the illuminating means 23 by which the objects are seen directly of substantially greater candle power than that of the illuminating means 15 which reflects the objects. Due to the fact of using a 5 darkened transparent material an ideal mirror results when the illuminating means 15 is functioning and the bulbs can therefore be of a low candle power. In order to procure substantially the same effect to the eye when the objects are 10 being viewed directly and the illuminating means 23 is functioning it is desirable to make these 15 bulbs of a much greater candle power.

Changes in details of construction and arrangements of parts may be made by one skilled in the 20 art without departing from the spirit of the invention.

I claim:

1. An advertising device having in combination a cabinet comprising side walls, a bottom wall, 25 a top wall and a rear wall, said top wall comprising a removable member upon which a picture or other indicia may be carried and a removable part in said rear wall upon which a picture or other indicia may be carried, a sheet of transparent darkened material angularly disposed between said side walls and dividing said cabinet into two compartments, a transparent member for supporting articles to be displayed, said transparent supporting member being spaced 30 from and substantially parallel with said top wall, illuminating means above and toward the rear upper end of said sheet of darkened transparent material and said transparent supporting member, other illuminating means on the opposite side of said sheet of darkened transparent material, and means for alternately operating said illuminating means.
2. An advertising device having in combination a cabinet comprising side walls, a bottom wall, 40

a top wall and a rear wall, a sheet of transparent darkened material angularly disposed between said side walls and dividing said cabinet into two compartments, a transparent member 5 for supporting articles to be displayed, said transparent supporting member being spaced from and substantially parallel with said top wall, a member adapted to carry advertising and forming a front wall for the compartment formed by said top wall and said transparent supporting member, illuminating means above and toward the rear upper end of said sheet of darkened transparent material and said transparent supporting member, other illuminating means on the opposite side of said sheet of darkened transparent material, means for alternately operating said illuminating means, and an extension formed at 10 the upper side and rear end of said cabinet, the front wall of said extension being formed of a member adapted to carry advertising. 15

3. An advertising device having in combination a cabinet comprising side walls, a bottom wall, a top wall and a rear wall, said top wall comprising a removable member upon which a picture or other indicia may be carried and a 25 removable part in said rear wall upon which a picture or other indicia may be carried, a sheet of transparent darkened material angularly disposed between said side walls and dividing said cabinet into two compartments, a transparent member 30 for supporting articles to be displayed, said transparent supporting member being spaced from and substantially parallel with said top wall, a member adapted to carry advertising and forming a front wall for the compartment formed by 35 said top wall and said transparent supporting member, illuminating means above and toward the rear upper end of said sheet of darkened transparent material and said transparent supporting member, other illuminating means on the opposite side of said sheet of darkened transparent material, and means for alternately operating 40 said illuminating means.

CARL G. SPANDAU.
